UNITED STATES PATENT OFFICE.

JOHN M. CAMPBELL, OF NEW CASTLE, PENNSYLVANIA, ASSIGNOR OF ONE-HALF TO WILLIAM G. CAMPBELL, OF NEW CASTLE, PENNSYLVANIA.

SPACER.

No. 927,110.

Specification of Letters Patent.

Patented July 6, 1909.

Application filed August 13, 1908. Serial No. 448,382.

To all whom it may concern:

Be it known that I, JOHN M. CAMPBELL, a citizen of the United States, residing at New Castle, in the county of Lawrence and State 5 of Pennsylvania, have invented certain new and useful Improvements in Spacers, of which the following is a specification.

This invention relates to marking instruments, and more particularly to spacing instruments for marking siding etc., and has for its object to provide an instrument of this kind which may be adjusted to mark a plurality of points equidistant from each other, and which will be adjustable to vary the distance between the points marked.

Another object is to provide an instrument of this kind which will be simple and which may yet be adjustable to suit different conditions.

20 A further object is to provide a structure such that two or more of the instruments may be connected to produce a single longer instrument.

Another object is to provide a structure in 25 which certain of the marking parts may be moved out of operative position when desired.

Other objects and advantages will be apparent from the following description and it 30 will be understood that changes in the specific structure shown and described may be made within the scope of the claim without departing from the spirit of the invention.

In the drawings forming a portion of this 35 specification and in which like numerals of reference indicate similar parts in the several views, Figure 1 is a side elevation of the instrument, Fig. 2 is a view similar to Fig. 1, the alternate markers being raised out of 40 operative position. Fig. 3 is a view showing the opposite side from Fig. 1, disclosing the set screws. Fig. 4 is a vertical section taken on the line 4—4 of Fig. 1, through one of the marking rods. Fig. 5 is a longitudinal section taken on line 5—5 of Fig. 1 through the central pivot and binding clamp.

Referring now more particularly to the drawings, the present invention comprises a plurality of diagonal plates 5, arranged in a 50 parallel series as shown, and also a plurality of similar plates 6, arranged oppositely in parallel relation, and pivoted at their ends to the ends of the plates 5. The plates 5 and 6 thus cross at their centers, at which points 55 they are pivoted as shown at 7, the pivot

points at the ends of the plates being indicated at 8. At the ends of the instrument there are short plates 9, extending outwardly to a meeting pivot 10. There is thus formed a lazy tong of the usual type. The pivoting of the ends of the plates 5 and 6 is accomplished through the medium of blocks 12, having stems 13, passed through alining portions 14 formed in the ends of the plates 5 and 6. The blocks 12 have vertical passages 65 15 formed therethrough, and communicating with these passages 15, there are horizontal passages 16, opening through the outer faces of the blocks, and receiving set screws 17. The blocks 12 are thus arranged in vertically 70 alining pairs, and the passages 15 of the alined blocks registered for the reception of vertically extending marking rods 18, which are slidably engaged in the passages for vertical movement. The set screws 17 are oper- 75 able to impinge against the rods 18, thus holding the latter against movement. The lower ends of the rods 18 are sharpened at 18', to form marking points. The extremities 14' of the stems 13, opposite to the blocks 80 12, are provided with transverse passages 14^a, for the reception of cotter pins 19, which hold the stems with the blocks in position. It will thus be observed that certain of the 85 marking rods may be raised out of the plane of the lower ends of the remaining rods, to vary the marking, and when it is desired to produce an unusually long instrument, the plates 9 are removed, and the ends of the outermost plates 5 and 6 of two instruments 90 are pivoted together.

Certain of the pivots 7, are formed by screws 20, passed through openings at the points of crossing of certain of the plates 5 and 6, these screws having thumb nuts 22 95 engaged therewith and operable to clamp the cross plates together to prevent movement of the several plates with respect to each other.

It will of course be understood that movement of the lazy tong structure longitudinally will vary the distance between the marking points 18.

What is claimed is:

In a marking instrument of the class described, the combination with a plurality of 105 plates disposed in diagonal parallel relation, of a second series of plates disposed diagonally in parallel relation to each other and in cross relation to the first named plates, the ends of the plates of the two series being dis- 110

posed in overlapped relation, and the corresponding plates of the two series crossing at their centers, pivot devices engaged in the centers of the crossed plates, pivot devices 5 engaged in the overlapped ends of the crossed plates, said second named pivot devices having enlarged heads at one end, the heads of the vertically alining pivot devices having registering passages formed therethrough, 10 marking rods slidably engaged in the alining

passages, and set screws engaged in the enlarged heads of the pivot devices for operation to impinge the marking rods to hold said rods against vertical movement.

In testimony whereof I affix my signature, in presence of two witnesses.

JOHN M. CAMPBELL.
